UNITED STATES PATENT OFFICE.

OTTO JOHN KUENHOLD, OF CLEVELAND, OHIO.

DRYING APPARATUS.

Application filed August 10, 1923, Serial No. 656,701. Renewed October 3, 1928.

This invention relates to drying apparatus, such as is used, for example, in household laundries and the like. More particularly, the invention relates to drying apparatus of cabinet form including an air heating chamber, a clothes drying chamber, suitable devices on which the clothes may be supported, and the necessary means for producing proper flow or circulation of air through the drying chamber.

The objects of the invention are to provide improved drying apparatus of the form described in which the cabinet is of simple construction and may be readily erected and installed and includes parts arranged in convenient form for shipping or storage and adapted to pass through a relatively small door or other opening; to provide an improved arrangement for causing the flow of heated drying air over or around the material to be dried; to provide an improved arrangement of racks or supporting devices for the material to be dried; and finally to secure greater efficiency and speed of operation as regards the drying effect.

Further objects of the invention are in part obvious and in part will appear more in detail hereinafter.

In the drawing, Fig. 1 is in part a front elevation, showing one of the cabinet doors open, and in part a broken out sectional elevation on the line 1—1, Fig. 2; Fig. 2 is a sectional plan view on approximately the line 2—2, Figs. 1 and 4, parts being broken out to expose interior parts; Fig. 3 is a sectional plan view on the line 3—3, Fig. 1; Fig. 4 is a sectional elevation of the lower part of the device on the line 4—4, Fig. 2; Figs. 5, 6, 7, 8 and 9 are sectional plan views, illustrating in somewhat conventional form other arrangements of drying racks; and Figs. 10 and 11 are respectively an elevation and a sectional plan view, showing details of the racks.

Referring to the drawings, the apparatus comprises a cabinet 1, of any suitable material, such as galvanized steel or iron, and of any suitable size or shape, being here shown as rectangular. Said cabinet comprises upper and lower portions 2, 3, the upper portion forming a relatively large clothes drying chamber 4 in which are located suitable means described more fully hereinafter, for supporting the clothes or other material to be dried, and the lower member including an air heating chamber 5, the heating devices and the means for controlling the

flow of air through the apparatus. The two casing members are formed as separable units to facilitate manufacture and for convenience in shipping, storing and transportation to the place of use. For example, the lower casing member is provided with suitable feet 6 adapted to rest upon the floor or other support, a floor 7, end walls 8 and side walls 9 all formed of sheets or plates joined at their edges in the usual manner of such sheet metal work. Upon the side and end walls is located a horizontal partition or wall 10 provided with two openings 11, 12, both preferably provided with removable screens 13 for collecting lint and foreign substances. This wall 10 forms a part of the upper cabinet unit and also the means for removably connecting it to the base, for which purpose its edges are bent downwardly into U-form, as at 14, to sleeve over the base and also receive the lower edges of the side and rear walls 15, 16 of the upper cabinet member. Said upper member has a roof 17 and one or more, two being shown, of suitable hinged doors 18. It may be lifted from the lower unit and the latter is of such size and proportions as to enable it to be placed inside of the upper unit for packing, storage or shipping, the arrangement also enabling each unit to be carried individually through a small door or down a narrow cellar stairway to the place of use, where the two units are assembled by placing the upper unit in position on the lower.

Within the lower cabinet member are located the air heating devices, such as the gas or other heater 20 supplied with fuel from any suitable source and usually provided with a screened air inlet 21. The heated products of combustion from said burner rise through a chamber 22 and pass through a series of vertically elongated horizontally extending pipes or conduits 23 connecting said chamber to a hollow header or manifold 24 from which they flow through a horizontal pipe 25 to a vertical pipe 26 leading to the chimney or other outlet. In one of said pipes, as in pipe 25, is a rotatable valve or damper 27 actuated by rod 28 having a handle 29 exposed on the front wall of the casing.

The air for drying the clothes is circulated through the cabinet and during its flow therethrough is heated by but without actual contact or mixture with the products of combustion. In the arrangement shown the drying air enters the lower cabinet member through

the inlet pipe 30 opening directly to the atmosphere and in which may be located a suitable adjustable valve or damper 31 controlled by the handle 32. The incoming air flows 5 horizontally from right to left in Fig. 1, entering chamber 5 and being deflected upwardly by the deflector plates 33 so that it passes between the series of neighboring heating pipes 23 and thence through the screened 10 opening 11 to the drying chamber 16. It being assumed that the doors are closed, the heated air rises in the drying chamber 16 and follows approximately the course of the 15 arrows in Fig. 1, passing upwardly, then to the right and then downwardly and flowing out from the drying chamber through the screened opening 12 leading to a chamber or passage 34 from which it flows through an opening in the end wall of the lower unit to a 20 passage 35 in a pipe or conduit 36 rising along one end of the cabinet and surrounding the pipe 26, pipe 36 being larger than said pipe to leave the annular passage 35 around the pipe 26.

25 The effect of the telescoped or co-axially arranged pipes 26 and 36 is to secure an increased draft of drying air through the apparatus due to the flow of the heated products of combustion in pipe 26. Said pipe serves 30 as a heater to heat and therefore expand the rising air current in the annular passage 35 and thereby induces and accelerates the draft. By proper regulation or adjustment of the 35 position of dampers 31, 27, the air current may be caused to flow at any desired speed so as to efficiently dry the material in the least possible time.

Within the chamber 16 are located the racks 40 or other devices for supporting the clothes or other material to be dried. These racks may be of any suitable form but preferably include a series of like frames normally supported within the chamber in parallel vertical planes to secure the greatest capacity and 45 best distribution of the materials in the drying chamber. In all arrangements of racks shown in the drawings there are four racks in separate vertical planes, the rear rack comprising a series of horizontal bars 37 spaced from the back wall of the casing and lying in 50 parallel horizontal relation in the same vertical plane. The remaining three racks are movably mounted so as to be capable of being moved to a position extending outwardly 55 from the drying chamber for convenient access to the inner racks for applying thereto and removing therefrom the materials to be dried. Preferably the racks are so proportioned and arranged as to enable them to lie 60 in spaced parallel vertical planes when in position in the drying chamber and in parallel position, or at least nearly so, when projected outwardly from the casing, thereby affording maximum access to all racks for loading 65 and unloading the same.

In the arrangement shown in Fig. 1, each of the three forward racks comprises two vertically extending side bars or pipes 40 connected by horizontal cross bars 41, the three racks being identical as regards the side and 70 cross bars for convenience in quantity production. One of the side bars has secured to its upper and lower ends arms 42 provided with pivot pins 43 entering vertically aligned openings in the roof and floor of the drying chamber, although the upper opening may be slightly advanced, or in other words, slightly nearer to the door opening than the lower so that the racks have a natural tendency to 75 swung outwardly or to open position. The arms 42 for the several racks are of different lengths, as shown in Figs. 1 and 3, each successive set of pivot pins from front to rear being advanced or stepped to the right one step. As a consequence, when the three forward racks are swung outwardly they lie 80 closely adjacent and in parallel relation enabling them to be readily loaded and unloaded with maximum degree of access to all 85 racks. To releasably hold the racks in drying position the swinging end bars 40 are provided with pins 44 adapted to engage notches or recesses in an inclined bracket member 45 attached to the end casing wall. Such a bracket member may be fastened to 90 each end wall and two sets of pivot openings are provided in the roof and floor so that the racks may be readily installed to swing from the right or from the left, according to convenience in the particular place in which the 95 dryer is installed.

Figs. 5 to 9, inclusive, show other arrangements of racks which also can be swung out into approximately parallel relation. For example, in Fig. 3, the pivots for the successive racks carried by the arms 42 are offset or in stepped relation in a direction parallel to the planes of the racks when the dryer is closed. In Fig. 5 the pivots are offset different distances normally or perpendicular to the planes of the racks and in this arrangement, also, only one bracket 45 is employed so that the racks at their other ends lie closer to the end wall of the casing than in the form shown in Fig. 3. However, extra 110 holes may be provided in the opposite end wall of the casing so that the bracket 45 can be attached to either end wall and the racks may be reversed to swing from the right, if desired.

In Fig. 6, the pivots for the several racks are offset in the planes of the racks by bodily displacement of the racks relative to each other so as to locate them in stepped relation. The pivots for all racks, however, are each located at the same point as regards its respective individual rack. Also, the bracket 45^a is curved due to the peculiar arcs of swing 115 of the several pins 44.

In Fig. 7 the racks are directly opposite 120

or in registration with each other but the pivots therefor are stepped at different distances from the end bars in a direction parallel with the planes of the racks.

5 In Fig. 8 the pivots for the several racks are offset or stepped both parallel with and perpendicular to the planes of the racks, while in Fig. 9 the pivots of the first and third racks are offset from the centers of the posts 10 in opposite directions, one forwardly and the other rearwardly, while the pivot for the second rack is in the axis of its post.

While both the vertical and horizontal members of the racks may be made of wood 15 with mortised joints, as is usual, I preferably specially form the racks in a manner to avoid warping either from the effect of moisture on the wood itself or due to the weight of materials hung on the racks. Figs. 10 and 20 11 illustrate the upper corner of a rack so constructed. The vertical posts 40 are light metal tubes or pipes of stock size, while each horizontal bar 41 has its end portions split, as at 41^a, and provided with an opening so 25 that the two ears 41^b formed by the split may be made to embrace the bar 40. When assembled in proper position the parts are clamped together by a bolt 41^c. With such an arrangement all parts are firmly held together without liability of warping and the 30 arms 42 may be suitable metal members threaded, pinned or otherwise secured to the ends of the pipes 40. It should also be noted, particularly by reference to Fig. 1, that the 35 pivot pins for the racks are elongated vertically and the arms 42 normally lie below the roof 17 of the cabinet. Therefore, as each rack is turned back into drying position its pin 44 rides up along the inclined edge of the 40 bracket 45 with slight upward motion of the entire rack until said pin reaches its position in the bracket notch or recess where it is releasably held by gravity.

Other arrangements obviously can be resorted to, but in all cases either the pivots 45 alone, or the racks themselves, or both racks and pivots are offset or stepped either parallel to or perpendicular to or both the planes of the racks. The effect is to secure closely 50 nesting or neighboring parallel relation of the racks when open as well as parallel spaced relation when closed.

What I claim is:

1. Drying apparatus, comprising a cabinet 55 provided with an upper drying chamber and a lower heating chamber with a horizontal wall separating the same, said cabinet being in two parts separable at approximately the plane of said horizontal wall, and one of said 60 cabinet parts being adapted to contain the other for shipping and storing purposes.

2. Drying apparatus, comprising a cabinet provided with an upper drying chamber and a lower heating chamber with a horizontal wall 65 separating the same, said cabinet being in

two parts separable at approximately the plane of said horizontal wall, and said wall having telescoping connection with both the lower and upper cabinet parts.

3. Drying apparatus, comprising a cabinet 70 provided with an upper drying chamber and a lower heating chamber communicating with each other through an opening in a horizontal separating wall, heating means in said heating chamber provided with an outlet to 75 a vent pipe, and an exhaust air conduit surrounding said vent pipe and communicating with said drying chamber for carrying away the moisture-laden air.

4. Drying apparatus, comprising a cabinet 80 provided with an upper drying chamber and a lower heating chamber communicating with each other through an opening in a horizontal separating wall, heating means in said heating chamber provided with an outlet to a 85 vent pipe, and an exhaust air conduit surrounding said vent pipe and communicating with said drying chamber for carrying away the moisture laden air, said vent pipe and said exhaust air conduit being vertically disposed at one side of the cabinet.

5. Drying apparatus, comprising a cabinet including heating and drying chambers, an outlet pipe for said drying chamber, a heating drum within said heating chamber, and 95 a vent pipe for said drum having its lower end portion passing through said drying chamber outlet pipe.

6. Drying apparatus, comprising upper and lower casing units separable as such, said 100 upper unit being provided with a drying chamber and said lower unit being provided with a heating chamber, means providing communication between said chambers when said casing units are in assembled relation, 105 an exhaust air conduit communicating with said drying chamber for carrying away moisture laden air, heating means in said heating chamber, a casing in said heating chamber for enclosing said heating means, air supply 110 means for said enclosing casing, air supply means for said heating chamber, and an exhaust conduit for said enclosing casing for carrying away the products of combustion.

7. Drying apparatus, comprising separable 115 upper and lower casing sections, said upper casing section being provided with a drying chamber and said lower casing section being provided with a heating chamber, heating means in said heating chamber, a casing in 120 said heating chamber for enclosing said heating means, a vent pipe for said heating casing in said lower casing section, means providing communication between said chambers for the flow of heated air from said heating chamber to said drying chamber, and an exhaust passage for said drying chamber arranged within said lower casing section.

8. Drying apparatus, comprising separable 125 upper and lower casing sections, said upper 130

section being provided with a drying chamber and said lower chamber being provided with a heating chamber, heating means in said heating chamber, a casing in said heating chamber for enclosing said heating means, means providing communication between said chambers for the flow of heated air from said heating chamber to said drying chamber, an exhaust passage for said drying chamber

having a portion arranged within said lower 10 casing section, and a vent pipe for said heating casing having a portion lying within the drying chamber exhaust passage portion which is arranged within the lower casing section. 15

In testimony whereof I hereby affix my signature.

OTTO JOHN KUENHOLD.
